JOHN LO VERDE AND ANTHONY TUBILO, OF ROCHESTER, NEW YORK, ASSIGNEES OF ONE-SEVENTH TO CHARLES J. MONDO, OF ROCHESTER, NEW YORK.

DESIGN FOR A CHILD'S VEHICLE.

60,250.

Specification for Design.

Patented Jan. 17, 1922.

Application filed September 18, 1920. Serial No. 411,316. Term of patent 3½ years.

To all whom it may concern:

Be it known that we, JOHN LO VERDE and ANTHONY TUBILO, said JOHN LO VERDE a citizen of the Kingdom of Italy and said ANTHONY TUBILO a citizen of the United States, residing at Rochester, in the county of Monroe and State of New York, have invented a new, original, and ornamental Design for a Child's Vehicle, of which the following is a specification, reference being had to the accompanying drawing, forming part thereof.

Fig. 1 is a perspective view of the child's vehicle showing our invention.

We claim:

The ornamental design for a child's vehicle as shown.

In testimony whereof we affix our signatures.

JOHN LO VERDE.
ANTHONY TUBILO.
